United States Patent Office.

R. W. CAMPBELL, OF SPURGEON, INDIANA.

Letters Patent No. 92,160, dated July 6, 1869.

IMPROVEMENT IN WHEAT-DRILLS.

The Schedule referred to in these Letters Patent and making part of the same.

To all whom it may concern:

Be it known that I, R. W. CAMPBELL, of Spurgeon, in the county of Pike, and State of Indiana, have invented a new and useful Improvement in Wheat-Drills; and I do hereby declare that the following is a full and exact description of the same, reference being had to the accompanying drawings, and to the letters of reference marked thereon.

This invention relates to certain improvements in wheat-drills, whereby the plows thereof are raised and lowered, and their depth of action regulated at will; also, to a device for measuring ground, as will hereinafter more fully appear.

In the drawings—

Figure 1 is a sectional view of my invention through the line $x-x$, fig. 2.

Figure 2 is a plan view of the same, with seat detached.

To enable others skilled in the art to make and use my invention, I will proceed to describe fully its construction and operation.

A' represent the side beams of the machine, connected in front by the cross-beam A'', and near the centre by the beam A''', to which is attached the driver's seat a.

a' represents a transverse rod immediately in the rear of the beam A'', on which are pivoted the bifurcated arms a'' of the beams a''', the same running backward a little beyond the cross-beam A''', where they bend downward, forming an acute angle, and terminate at the plow-points D.

B represents a transverse rod, pivoted in the projections B' B'', in the rear of the beam, which supports the driver's seat. The rod B is provided with the arms B'' B''', &c., which curve downward, and are attached, by chains or otherwise, to the beams a''', their function being to elevate the same with their attachments, which is accomplished by means of the curved rod B''', the same being rigidly attached to the centre of rod B, and, passing under the beam A'', is attached, by means of the connecting-rod b, with the rear end of the tongue b', which has a longitudinal motion in bearings between the braces b'' b''', and in the under surface of the beam A'', which is provided with a friction-roller, x. The tongue is prevented from being wholly withdrawn by a horizontal slot within the same, inside the bearing, which is provided with a pin passing through the same, and arresting it at its extreme outward limit.

b'' represents the double tree, which is attached to the tongue by the pivot b''', the same passing through an elongated slot, C, in the plate C', to admit of the sliding of the tongue.

In the rear of the double-tree b''', and pivoted to the braces b'' b'' by the bifurcated rod C'', is the lever C''', near the centre of which is the vertical pin or pivot c, which passes through the beam A'', and drops into a corresponding orifice in the tongue b', when the same

comes in connection therewith, thus holding it securely in position.

To release the pin c, the treadle c' is provided, one end of which is pivoted to the rear end of the lever C''', and the other to the beam A''. By depressing the foot-piece c', the other end of the same is raised, and with it the lever C''' and pin c.

To the descending sides of the angular beams a''' are riveted the sheet-iron tubes or boots c'', which latter terminate a little above the plow-points D, which are rigidly attached to the beams a''', constituting the seed-drills.

D' represents coulters, the upper ends of which are also rigidly attached to the beams a''' near the angle thereof, these lower ends being strengthened by the diagonal braces D'', which are attached to the rod a'.

To the lower ends of the coulters D' are attached the bifurcated guides D'', which are rendered adjustable by means of the orifices d d', &c., in the coulters, their function being to regulate the depth of action of the coulters and plows.

d' represents a kind of odometer, which consists of the plate d', with bifurcated arms d'' d''', pivoted to the beam A'' and the parallel arm d', which, in connection with the plate d', forms the bearings of the cog-wheels d'' and d''', the former of which engages with a projection, E on the axle E', and, at every revolution of the latter, is revolved one tooth. It is also provided with a projection, which engages the other wheel d'', which is connected by its shaft with an eccentric, E', on the outside of the plate d', which latter is provided with a tooth or projection.

e represents a spring, operating in connection with the eccentric E', which bears closely on the periphery of the latter, and, when raised by the projection, snaps down with sufficient force to cause a report, thereby indicating every revolution of the wheel d''. This device may be regulated in any desirable manner to effect the desired end.

F represents the seed-box, which is divided into compartments, to prevent the seed from accumulating in either end on uneven ground.

At the bottom of the compartments are the usual openings, over which revolve the stirrers F', on the shaft F'.

The apertures in the bottom of the seed-box are regulated by a horizontal slide, operated by the lever F' and connecting-rod f.

f' represents a cog-wheel on the axle E', which engages, through the idle-wheel f'', with the wheel f''', on shaft F', and imparts motion thereto.

The connection of the seed-box with the boots c'' is made by leather or other tubes, which extend from the orifices in the bottom of the same down into the tubes, and are constructed somewhat smaller in size, to admit of the same having a free vertical motion thereon.

The operation of my invention is as follows:

When the machine is in working order, with the plows at their full depth, it is necessary only to back the team, by which means the sliding tongue is forced back until the orifice in the same reaches the pin or pivot *c*, which falls therein, firmly securing it in place. This motion is communicated through the connecting-rod *b*, to the curved rod *B*³, and thence to the pivoted rod *B*, which is turned upward in its bearings, carrying with it the arms *B*², *B*³, &c., which elevate the beams *a*, with their attachments. The team may be then set in motion, and by simply depressing the treadle *c'*, the tongue is drawn out and the plows fall.

The depth of the plows is regulated by moving the bifurcated guides *D*³ up or down, as above described. The quantity of grain delivered is also effectually regulated by the slide.

Having thus fully described my invention, What I claim as new, and desire to secure by Letters Patent, is—

1. The adjustable guides *E*³, in combination with coulters *D*¹ and drills *c*², or their equivalents, as and for the purpose set forth.

2. The above-described arrangement for elevating the drills, constructed substantially of the sliding tongue *b*', lever *c*', pivot *c*, treadle *c'*, connecting-rod *b*, curved rod *B*', rod *B*, with arms *B*² *B*³, &c., arranged and operated substantially as described.

This specification signed and witnessed this 18th day of February, 1869.

R. W. CAMPBELL.
